FIG.

By

John N. Scott

his Attorney

UNITED STATES PATENT OFFICE.

BENJAMIN F. LINDSLEY, OF MANSFIELD, OHIO.

BEDSPRING.

Application filed February 9, 1923. Serial No. 617,972.

To all whom it may concern:

Be it known that BENJAMIN F. LINDSLEY, a citizen of the United States of America, residing at Mansfield, in the county of Richland and State of Ohio, has invented certain new and useful Improvements in Bed-springs, of which the following is a specification.

The present invention consists of improvements in the structure described and claimed in Patent No. 812,939, bearing date of February 20, 1906, and entitled "bedspring," whereby the old objects are retained and new objects attained in combination therewith as herein particularly referred to.

One of the objects of the invention consists in mounting and supporting a series of conical coiled springs on suspended bars in such a manner as to permit the mounting of said springs substantially throughout the entire area of the bed spring as a whole, so as to provide yielding or resilient means to support the body of the user of the bed spring at all points, which result is accomplished in the present invention by the method of attaching the suspension bars to the risers and connections of the frame.

Further objects are to provide means of preventing a direct pull being exerted on the series of conical springs to prevent them from being drawn in irregular or uniform positions, when pressure is being exerted on the side, as for instance in the event a person sitting on the side of the bed, and to provide means of attaching and removably locking the coiled springs to the bars upon which they are mounted.

Further objects of the invention are to provide means for bracing the entire spring bed structure at or about the center portion thereof, through the medium of a brace suspended from the side bars of the frame, and to construct the spring frame so as to permit the attachment of the side bars of the frame in a position to be directly over the side rails of the bed spring and bed frame.

These and other objects are attained by the construction of a bed spring illustrated in the accompanying drawings in which:

Figure 1 is a plan view of the bed spring showing the bed spring assembled.

Figure 2 is a side view of Figure 1, taken on the lines 1-1.

Figure 3 is a perspective fragmentary view of one corner of the bed spring. 55

Figure 4 shows the means of attaching and locking the conical springs to the supporting bars.

Figure 5 shows a section of the chain top.

Figure 6 shows a side view of one of the 60 compression springs.

Figures 7 and 8 show plates for connecting parts of the chain top to the frame.

Figure 9 shows a cross sectional side view of the bed spring and means of bracing and 65 connecting the supporting bars in uniform and spaced relation to each other.

As stated in the objects set out herein, the present invention consists in retaining the results obtained in the patent identified 70 herein, in combination with new results by reconstructing, assembling and combining the original elements of the patent herein identified with others in such a way as to obtain new results and more efficient results than obtained by the structure shown and described in the patent herein identified.

In the construction of a bed spring to obtain the new results set out in the objects 80 as herein set forth, risers 1 are provided, which are formed to curve upwardly, rearwardly and inwardly thereby forming rounded corners on the bed spring when the same is assembled. The risers are provided with inwardly projecting lugs 2 and 3. The lugs 2 and 3 are positioned on the risers adjacent to the top and bottom thereof in spaced relation to each other.

Attention is called to the fact that the 90 risers are formed in rights and lefts. The top portions of the risers project inwardly in opposed relation and in alinement with each other. Side rails 4 and 5 preferably made tubular in cross section, are secured to 95 the bosses 6 of the risers. End bars 7 and 8, preferably made angular in cross section, are secured to the inwardly projecting curved ends of the risers by bolts 9 or the like, the upper portion of the end bars being 100 positioned on a plane with the top of the risers. Auxiliary end bars 10 and 10' (preferably made angular in cross section) are attached to the lugs 2-2 of the risers in 105 spaced relation to the angle bars 7 and 8, and at different horizontal planes.

The construction of the bed spring so far describes the frame consisting of duplicate right and left risers positioned to form the corners of the bed spring frame, having end bars secured thereto in spaced relation to each other by bolts 9 or the like. The construction described comprises the stationary frame of the bed spring. A series of supporting bars 11 are yieldingly suspended from the auxiliary bars 10, by a series of coiled springs 12, which are attached to the ends of the bars 11 and to the auxiliary bars 10.

A series of conical springs 13 having their ends 14 at the small portion of the cone turned (as shown at 14) are mounted upon and fitted to apertures formed in the supporting bars 11. The turned portion provides means of locking the conical springs to the supporting bars 11 as shown in Figure 4. The upper portion of the conical springs 15 are connected together sidewise by short links of chain 16. Chains 17 are interposed between the series of conical springs and cross the short links 16 at right angles and are connected thereto.

A series of expandable springs 18 are connected to the end angle bars 8 at one end and the opposite end is connected to tie plates 19. Chains 20 and 21 are connected to the tie plates at one end and their opposite ends are connected to links 22 which are in turn connected to the end series of conical springs 13.

The construction as described provides a chain top which yields with the conical springs to permit a downward and horizontal yielding movement simultaneously. The expandable springs 18 and 12 yield in a horizontal direction and the conical springs in a vertical direction, thereby providing a bed spring that conforms and yields to every irregular movement of the body of the user, irrespective of the position of the body of the user upon the bed spring.

In order to maintain and hold the series of springs in uniform position and at the same time permit yielding movement of all of the springs and automatically maintain and return the springs to their normal relation with respect to each other, side bars 23 and 24 are provided and connected by expandable springs 25 and 26 to the lugs 3 of the risers. Continuous chains 27 and 28 are interposed between the side bars and the side series of conical springs and are yieldingly connected through the medium of the plates 19 and expandable springs 18 to the end bars 8.

The continuous chains 27 and 28 are connected to conical springs at the top thereof by short chains 29. The continuous chain 27 and 28 are also connected to the side bars 23 and 24 through the medium of the links 30 between each series of conical springs. It will be noted that yieldingly

side bars 23 and 24 are not connected directly to the conical springs; therefore when pressure is exerted upon the side of the bed as for instance when the user sits on the side thereof a direct pull is not exerted on the top of the coil springs but indirectly through the medium of the yielding chains 27 and 28, thereby preventing the springs from being excessively pulled, stressed, or moved from their vertical positions.

It will be observed that this construction serves to maintain the entire series of conical springs in uniform position and regular with respect to each other, and provide means to automatically return the springs to normal position when the pressure is released upon any part of the area of the top of the bed spring.

To maintain the series of supporting bars 11 in uniform spaced relation to each other and at the same time tend to support same from the side bars, a brace 31 is provided to which the supporting bars 11 are attached. The brace 31 is secured to the supporting bars 11 and is suspended from the side bars 23 and 24 by the inclined members 32 and 33 which are attached to the side bars 23 and 24 at one end and to the brace 31 at the other end as shown in Figure 3.

The brace provides means of strengthening the center of the bed spring, maintains the supporting bars 11 in uniform relation to each other, holds the side bars in proper relation to each other and tends to maintain the entire area of the top of the bed spring in normal position.

Attention is called to the fact that the members 32 and 33 are preferably attached toward the center of the brace bar 31. This method of connecting the supporting members to the brace bar 31 serves also to maintain the conical springs in uniform and normal positions whether subject to pressure or not.

Angular plates 34 as shown in Figure 8 are used to connect the continuous chains and springs at the sides of the bed spring.

Reference numeral 35 refers to lugs formed integral with the risers to prevent sidewise or lateral movement of the bed spring.

I claim:

In a bed spring, risers extending rearwardly from the body portions thereof, thence inwardly at the top, angle end bars, means to secure a pair of angle end bars to said risers in spaced apart relation vertically and longitudinally from each other, supporting bars yieldingly connected to one of each pair of the angle end bars, a plurality of conical springs removably mounted on said supporting bars, a series of chains connecting the top portions of said conical springs, whereby the top portion of the springs and chains provide the top of the

bed spring, and side bars yieldingly and independently connected to the risers and positioned directly over the side rails of the bed spring, flexible connections between said side bars and the adjacent chains and connected to the latter intermediate the connections of said chains and springs, a brace bar underlying and connected to the supporting bars, and inclined brace members extending from the ends of such brace bar ¹⁰ and connected to said side bars.

In testimony whereof I affix my signature.

BENJAMIN F. LINDSLEY.
